United States Patent Office.

JACOB K. NELSON, OF GREENPOINT, NEW YORK.

Letters Patent No. 63,741, dated April 9, 1867.

IMPROVED SCREW-CUTTER.

The Schedule referred to in these Letters Patent and making part of the same.

TO ALL WHOM IT MAY CONCERN:

Be it known that I, JACOB K. NELSON, of Greenpoint, in the county of Kings, and State of New York, have invented a certain new and useful improvement on Screw-Cutting Devices, applicable also to other purposes, of which the following is a full, clear, and exact description, reference being had to the accompanying drawing, forming part of this specification, and in which—

Figure 1 represents a partly sectional longitudinal view of a ratchet wrench, with my improvement applied to it, as constructed or arranged for cutting screw-threads on a pipe or rod.

Figure 2, a transverse sectional view of the detachable socket fitted as if and shown in the act of severing a pipe; and

Figure 3, a similar view of said socket fitted as for unscrewing or screwing up work.

Like letters indicate like parts throughout the several figures.

The nature of my invention consists in a novel construction of detachable sockets applicable mainly to ratchet wrenches, and provided with loose or detachable chasers, or cutters, or grippers, according to the purpose the tool is designed to be applied to, and separately adjustable in radial directions within the socket from the outside of the head of the wrench.

Referring to the accompanying drawing, A represents the handle or stock of a ratchet wrench; B its revolving head; and C its double catch or pawl, which should be made slotted to permit of the passage through it, as the head revolves, of projecting ends or heads of screws, *a*, entered radially through the revolving head. D is the detachable socket, fitting and locking, it may be, by screws fitting holes *b* and projections *c* within, or so as to form a revolving attachment to the revolving head B. This socket D is fitted, if for cutting a screw-thread, on the outside of a pipe, with loose and detachable radial chasers, E, and preferably with intermediate similarly fitted steadyng blocks F, all of which are adjustable inwards to take their hold on the pipe by the screws *a*, and which may be so set to act on different diameters of pipe without removing the socket, or the latter may be taken out of the revolving head and other chasers and steadyng blocks substituted, according to the pitch of the screw to be cut. Being loose and detachable these chasers and steadyng blocks may readily be changed, and being small and cheap, or simple devices, a large number of them may be furnished a wrench without materially adding to the cost, as compared with separate necessary sockets having the chasing surfaces on them. Furthermore, instead of the chasers and steadyng blocks having screw-threads on them, a similar shaped block, G, having a dividing cutter formation, *d*, and constituting a positive cutter, may be inserted in one of the radial slots *e* of the socket and plain-faced steadyng or gripping blocks H in the other radial slots *e* thereof, for severing a pipe, as represented in fig. 2; or the radial slots *e* may be fitted wholly with gripping blocks, as represented in fig. 3, for screwing or unscrewing work, all of such blocks, whether chasers, dividing cutters, or mere grippers, being radially adjustable by the screws *a*, and being separate and detachable devices to or within the socket D.

A tool thus constructed, provided, and operated, will be found serviceable in numerous instances where space to work a regular screw-cutter, divider, or screw-wrench is contracted, and being so readily convertible to perform different functions or offices, will be a desideratum in a variety of trades.

What I claim as my invention, and desire to secure by Letters Patent, is—

In combination with the revolving head B the detachable socket D, fitted with loose or detachable blocks E F G or H, forming chasers, cutters, steadyng blocks or grippers, and made capable of radial adjustment from the outside of the revolving head of the hand tool or wrench, substantially as and for the purposes herein set forth.
